UNITED STATES PATENT OFFICE.

CHARLES JOSHUA LANE, OF LONDON, ENGLAND, ASSIGNOR TO CYRIL FRANK
ELWELL, OF LONDON, ENGLAND.

APPARATUS FOR GALVANIZING OR OTHERWISE COATING ARTICLES.

1,392,509.

Specification of Letters Patent.

Patented Oct. 4, 1921.

Application filed August 6, 1920. Serial No. 401,768.

To all whom it may concern:

Be it known that I, CHARLES JOSHUA LANE, a subject of the King of England, residing at London, England, have invented 5 certain new and useful Improvements in Apparatus for Galvanizing or Otherwise Coating Articles, of which the following is a specification.

This invention is for improvements in or 10 relating to apparatus for galvanizing or otherwise coating articles and has for its object to provide means whereby the progress of the process may be tested and known without interrupting the process.

According to this invention there is provided in an apparatus for coating (for example, galvanizing) articles, the combination 15 with a closed container wherein the coating takes place, of an ante-chamber communicating therewith, and a test-piece, (for example, a rod) projecting through the wall of said ante-chamber and fitting a hole therein, and through the ante-chamber into the container, said test-piece being adapted 20 to be withdrawn from the latter in two stages, so that a portion of it whereon the coating is deposited can first be moved into the ante-chamber where the coating can harden, and then can be withdrawn for 25 inspection, with or without detent means engaging the test-piece to determine the stages of its withdrawal.

In a preferred form, the invention comprises in apparatus for coating articles, the 30 combination with a closed rotatable drum and a hollow supporting trunnion thereon forming the ante-chamber aforesaid, of a test-rod extending from outside the trunnion through a packing-gland on the end 35 thereof and through the trunnion into the interior of the drum, and detent means for indicating or limiting the withdrawal of the rod.

According to another feature of the invention the rod is formed with a notch or 40 notches and there is also provided a washer which is held against movement longitudinally of the trunnion, but hangs loosely on the rod so as to engage a notch thereon when 45 brought to register with it, with or without means for raising the washer clear of the notch to permit further withdrawal of the rod.

In the accompanying drawings, 50 Figure 1 is a central vertical section of so

much of a galvanizing apparatus as is necessary for the understanding of this invention;

Fig. 2 shows a preferred form of test-rod 60 for use with the apparatus shown in Fig. 1;

Fig. 3 is an end view of a further detail of the invention, and

Fig. 4 is a central vertical section showing a modified construction of the same detail. 65

Like reference characters indicate like parts throughout the drawings.

Referring to Fig. 1, the apparatus for galvanizing or otherwise coating articles comprises a closed rotatable drum 10. This 70 drum is supported at one end by a trunnion 11 provided with a central axial bore 12 communicating at one end with the interior of the drum 10. The other end of this bore is reduced in diameter at 13, and any desired or suitable form of gland with packing 14 is provided at the outer end of the opening 13.

The rod 15 as shown in Fig. 2 is inserted from outside through the packing 14 and 80 chamber 12 into the container 10. This rod is of such length that when it occupies the position shown in Fig. 1, the portion of it lying within the container 10 can receive a coating similar to the articles therein, and 85 then the rod can be withdrawn so as to bring this portion first into the space 12, which constitutes an ante-chamber to the container 10, and when the coating is hardened, it can be withdrawn through the packing 14 to enable the coating to be inspected. 90

In order to render as simple as possible the operation of withdrawal, it is preferred to provide a detent device governing each stage of the withdrawal of the rod, that is 95 to say, the rod is withdrawn until the first engagement of a detent takes place, and it is then known that the portion of the rod which is to be inspected is lying within the ante-chamber 12. During the further withdrawal of the rod, it is drawn out until the second engagement of the detent takes place, and it is preferred that this detent should be a positive stop to prevent the rod from being withdrawn entirely from the 105 orifice 13. This is particularly advantageous when the process for coating involves the interior of the container 10 being under pressure, as any escape of the contents through the orifice 13 is thereby prevented. 110 The detent means illustrated in Fig. 1 com-

prises a washer 16 whereof the central bore is countersunk to provide a comparatively sharp edge 17 on that side of the washer facing the drum 10. This washer is mounted in a cage-like structure, conveniently formed on the nut of the gland 14. This structure comprises a plate 18 carried on four pins 19. These pins are provided with spacing sleeves 20. The washer 16 lies between the plate 18 and the end of the gland-nut 14 so that its movement axially of the rod 15 is limited by them. The pins 19 with their sleeves 20 are so spaced apart that the washer has a certain amount of free lateral movement as shown most clearly in Fig. 3.

This washer is threaded on to the rod 15 so that it hangs thereon. The rod 15 is provided with a curved notch 21 and an angular notch 22 providing a shoulder 23. The notch 21 is so positioned that when the rod is withdrawn sufficiently far for that notch to engage the washer 16, the portion of the rod which has been coated is then lying within the ante-chamber 12. The shoulder 16 is so positioned that when it is engaged by the washer 23 on further withdrawal of the rod, the coated part of the rod is outside the trunnion and available for inspection of the coating. It will be seen, therefore, that no special care need be exercised in the withdrawal of the rod since the washer 16 drops into the notch 21 and thereby checks the withdrawal movement. This, however, is not a positive stop, since the rod has to be withdrawn farther. The notch 22 with the shoulder 23 does however constitute a positive stop since the washer will not ride up the shoulder.

It is sometimes required, however, that the rod shall be entirely withdrawn and to enable this to be done, means are provided to lift the washer up from its engagement with the shoulder 23, one such lifting means being illustrated in Fig. 3. A lever 24 is pivoted at 25 on any suitable fixed part of the machine, and an extension 26 of the lever is arranged to engage the edge of the washer 16. This extension may, if desired, be made of spring material so that it can yield to permit a pin 19 to pass it during the rotation of the drum.

In Fig. 4, a modified arrangement is illustrated. In this case the washer 16 has secured on it, or formed integrally with it a sleeve 27 which extends through the plate 18 to the outside thereof. This sleeve 27 is suitably formed without projecting parts at its outer end so that it can be grasped by the operator even although it is in rotation and lifted to clear the edge 17 of the washer 16 from the shoulder 23 and permit the further withdrawal of the rod 15.

It will be seen that if the constructions illustrated in Figs. 3 and 4, or other equivalent arrangements are used, the notch 21 need not be a curved notch, but may be replaced by a shoulder notch similar to the notch 22.

It will be seen that this invention provides means whereby the progress of the coating can be tested without interrupting the process and it will be appreciated that various modifications may be made in the construction of the parts according to the type of container in which the coating takes place; all such modifications are held to lie within the scope of the present invention as set forth in the appended claims.

What I claim as my invention and desire to secure by Letters Patent is:—

1. In an apparatus for treating material, a closed container wherein the treatment takes place, an antechamber communicating therewith, and a test-piece projecting through the wall of said antechamber, through said chamber and into said container whereby it is subjected to the treatment therein, said test-piece being adapted to be withdrawn in a plurality of stages. 90

2. In an apparatus for treating material, a closed container wherein the treatment takes place, an antechamber communicating therewith, a test-piece projecting through the wall of said antechamber, through said antechamber and into said container whereby it is subjected to the treatment therein, said test-piece being adapted to be withdrawn in a plurality of stages, and means for indicating the conclusion of movement 100 through each stage.

3. In an apparatus for treating material, a closed container wherein the treatment takes place, an antechamber communicating therewith, a test-piece projecting through the wall of said antechamber, through said chamber and into said container whereby it is subjected to the treatment therein, said test-piece being adapted to be withdrawn in a plurality of stages, and means preventing the accidental withdrawal of the test-piece. 110

4. In an apparatus for treating material, a closed container wherein the treatment takes place, an antechamber communicating therewith, a test-piece projecting through the wall of said antechamber, through said chamber and into said container whereby it is subjected to the treatment therein, said test-piece being adapted to be withdrawn in a plurality of stages and formed with a notch, a washer held against movement longitudinally of the wall of said antechamber and hanging loosely thereon so as to engage said notch when said notch is brought to 120 register with said washer. 125

5. In an apparatus for treating material, the combination of a closed rotatable drum, wherein the treatment takes place, a hollow supporting trunnion thereon forming an 130

antechamber to said drum, a packing-gland on the exposed end of the said trunnion, a test-rod extending from outside said trunnion through said packing-gland through 5 said trunnion into said drum whereby it is subjected to the treatment therein, said test-rod being adapted to be withdrawn in two stages, whereby the portion in the container is withdrawn into the trunnion in the first 10 stage and through the packing-gland in the second stage.

6. In apparatus for treating material the combination of a closed rotatable drum wherein the treatment takes place, a hollow 15 supporting trunnion thereon forming an antechamber to said drum, a packing-gland

on the exposed end of said trunnion, a test-rod extending from outside said trunnion through said packing-gland and through said trunnion into said drum, said test-rod 20 being formed with a plurality of notches, a washer outside said packing-gland hanging loosely on said test-rod and restrained from movement longitudinally of the trunnion so as to engage each of said notches 25 when brought to register with it and means for disengaging said washer from a notch to permit further withdrawal of said test-rod.

In testimony whereof I affix my signature. 30

CHARLES JOSHUA LANE.
